UNITED STATES PATENT OFFICE.

EUGENE S. BRADFORD, OF ST. LOUIS, MISSOURI.

ATTACHMENT-HOLDER DEVICE FOR FENCE-POSTS, POLES, &c.

SPECIFICATION forming part of Letters Patent No. 507,966, dated October 31, 1893.

Application filed October 5, 1892. Serial No. 447,866. (No model.)

To all whom it may concern:

Be it known that I, EUGENE S. BRADFORD, of the city of St. Louis, in the State of Missouri, have invented a certain new and useful Improvement in Attachment-Holder Devices for Fence-Posts, Telegraph-Poles, &c., of which the following is a full, clear, and exact description, reference being had to the accompanying drawings, forming part of this specification.

This invention relates to sheet or cast metal tubular or other hollow fence and hitching posts and telegraph and other poles, that are provided with elongated vertical slots at the several heights to which the wires, rods, or cables as the case may be are to be mounted, with holder attachments for said mount. The said holder attachments have curved inner arms, that when presented in registering position with said elongated slots freely enter the same, and are turned a quarter round transverse of said slots into their clamping position within said post or pole, the said holder having also outer arms that are then bent around to embrace the same externally. An outwardly projecting neck of the central stem forms one support for the wire or other mount outside said outer arms and said neck carries a retainer disk, connected with which disk and projecting therefrom there is a ring, the two overlapping hooks of which constitute the equivalent of an open or split ring, which also makes an efficient holder for cables or other mounts; and the invention consists in features of novelty hereinafter fully described and pointed out in the claims.

Figure I is a horizontal section, and shows a transverse section of the post or pole with the wire or other mount holder attachment secured thereto having a horizontal ring. Fig. II is a detail elevation of the post or pole and in the lower portion of said figure is shown the transitional position of the mount-holder, when seated in the elongated slot, just previous to being turned into its clamping position, its outer arms stretching in a straight vertical position, and having a horizontal ring and in the upper portion of the view a holder having a vertical ring is shown turned round into its clamping position, and said previously straight arms bent around the periphery of the post or pole, the base of

the rings being shown in section on the faces of the retainer disks. Fig. III is a vertical section, taken on line III—III, Fig. II, and shows the post or pole with its elongated slot, and the holder in its ultimate clamping position in the same, the ring being shown part in circumferential section where the vertical section line divides it; and Fig. IV is a vertical section, taken on line IV—IV Fig. II and shows the holder in its transitory position just after insertion, and previous to turning into its clamping position.

Referring to the drawings: 1 represents the metal tubular or hollow post or pole and 2 are elongated slots therein.

3 represents the combination attacher and holder device, which is made of malleable iron or other suitable metal, and is constituted of the following integral parts: namely the central stem 4, the pair of curved inner clamp arms 5, at the inner end of said central stem, the pair of outer embracing arms 6, the wire or other mount carrier neck 7, forming an outward extension of said central stem, the disk-head retainer 8, and the double overlapping hooks 9, which project outwardly from said disk-head retainer, and which double overlapping hooks together constitute the split or open ring 10.

The device is invented for fence and hitch posts as also telegraph and telephone attachments, and for any attachments in which barb and other fencing wires and metal strips as also metal rods are secured to posts for fencing, divisional, and hitching purposes; and for cable and wire attachments to telegraph and telephone poles, it being evident that glass and other insulators of ordinary construction may be used where bare electric wires are to be attached, and that there being no novelty in said insulators, they are not particularly shown and described. Also it will be understood that when describing the operation of attachment to a hollow or tubular post, the same description applies as definitely to the attachment to a telegraph or telephone pole or other object of attachment, to save needless repetition, and that I do not confine myself to the round form of the post as shown in the drawings, as the term tubular is used in its broad sense to define a hollow body of any shape, as in tubular bridges

which are preferably rectangular in transverse section.

- The means of attachment of my holders for the mounting of barb and other wires, cables, rods, &c., to hollow or tubular posts, &c., are as follows: The hollow posts 1 having been erected in position, and said posts provided with the elongated slots 2, which slots may be as numerous and located in accordance with the desired number and position of the attachment devices for the wires, &c., the curved clamp arms 5, on the inner ends of the central stems 4, of the holders 3, are presented in a vertical registering direction to and through the vertical elongated slots 2 (see Fig. IV and the lower attachment in Fig. II), and the holder with said clamp arms is then turned a quarter round, which brings said arms in transverse position across, and to each side of said elongated slot, thus firmly securing the attachment of the holder, the convex curved sides of said arms fitting the concave inner surface of the tubular post, (see Figs. I and III and in broken lines in the upper attachment of Fig. II.) The outer embracing arms 6, which also reach out integrally from said central stem 4, and the holder with its clamping arms are made preferably as stated of malleable iron, said arms 6 being bent around so as closely to embrace the periphery of the post (see Fig. I and the upper attachment of Fig. II). The holder is thus tightly held from both within and without said tubular post.
- If the construction is for a barb or other wire or metal strap fence, the line of wire or strap as the case may be is mounted on the bearer neck support 7, and at certain intervals along the line the tension of the wire is maintained after stretching taut by a turn or belaying of said wire around said bearer neck 7 of the holder, and the disk-head 8 of said holder retains the wire in position on its seat. The double overlapping hooks 9, which in connection form the open or split ring 10 project integrally from said disk-head 8, as shown in all the figures, a full view being shown in Fig. I, sections of the base stems of the hooks being shown in Fig. II, and vertical curvilinear sections of said overlapping hooks shown in Figs. III and IV, the said section lines in the two last named figures having cut away the overlapping points of the upper hooks. When the holder is for use with barb wire fences, or clothes line supports, the said overlapping hooks 9 that constitute the open or split ring 10 may if desired be dispensed with, and then the retainer disk 8 constitutes the outer finish to the holder.
- When, however, the device is used for suburban or residence fences in cities, the said open ring is preferably an element thereof, as it provides a convenient means as a holder attachment for the ornamental horizontal bars that enter into the construction of the fence and the extreme ends of said rods may have

mutual half cut away joints within said ring. Also the overlapping points of the hooks being preferably of malleable iron are readily closed around said fence rods to effect a tight grip of the same. Hitch posts are also thus to be constructed, and the open ring 10 when closed makes a convenient tie ring for hitching. When, however, the horses of a large number of vehicles are to be hitched in the neighborhood of some general resort, as a city hall, hitch bars are inserted and firmly held within the closed open rings 10, in connection with a line of posts.

When used as a holder attachment for telegraph and telephone hollow or tubular poles the said poles are provided with the same form of elongated slots as are the fence posts, said slots being located at such and as many of such points of elevation as it is required for the electric cable or wire to traverse, and the attachment holders are secured in said elongated slots and to said poles as has been already described in relation to the fence posts.

It will be seen that glass or other insulators can readily be secured in the open rings by bending the points of the double overlapping hooks within the outer grooves of said insulators. If it is desired to stretch bare wires through said holder rings, wires or cables can be passed through the overlapping hooks into the open rings, while other cables may be seated on the bearer neck 7.

The hollow or tubular posts and poles may be made of any desired form in cross-section, round, rectangular, angular, octagonal, &c., to best suit the especial purpose for which said posts or poles are to be used. Also the inner clamping and outer embracing arms respectively 5 and 6, it is evident are easily made conformable to the respective inner and outer surfaces of the posts or poles to which they are attached.

The open or split holder rings 10, may be secured to the fence or hitch post, or to the telegraph or telephone pole, in either a horizontal position, as shown in Fig. I, being arranged to be turned into said horizontal position, as shown in the lower portion of Fig. II and in Fig. IV, or they may when the exigencies of the case frequently make it preferable, be secured in a vertical position as shown in the upper portion of Fig. II and in Fig. III.

I claim as my invention—

1. In fence posts telegraph poles, &c., the combination of the tubular post or pole 1, and the central attachment stem 4 having a suitable wire holder integral therewith, and the arc shaped inner clamp arms 5, that hold inside said tubular post or pole; substantially as described.

2. In attachment holder devices for fence posts, telegraph poles, &c., the combination of the hollow posts or poles, provided with the elongated slots 2, the cable and wire at-

tachment holder having the central stem 4, the inner curve arms 5 and outer embracing arms 6; substantially as described.

3. In fence posts, telegraph poles, &c., the combination of the post or pole 1, provided with the elongated slot 2, and the wireholder 3, consisting of the central stem 4 the inner clamp arms 5, the outer embracing arms 6, and the cable and wire bearer neck 7, substantially as described.

4. In attachment holder devices for fence posts, telegraph poles, &c., the central stem 4 of the cable and wire holder 3, the inner clamp arms 5, the outer embracing arms 6, the bearer neck 7, and the retainer disk head 8, substantially as described.

5. In attachment holder devices for fence posts, telegraph poles, &c., the central stem

4 of the cable and wire holder 3, the inner clamp arms 5, the outer embracing arms 6, 20 the bearer neck 7 and the double overlapping hooks 9 that form the open or split bearer ring 10; substantially as described.

6. In fence posts, telegraph poles, &c., the combination of the hollow post or pole 1, provided with the elongated attachment slot 2, and the cable and wire holder 3 consisting of the central stem 4, the curved inner clamp arms 5, the outer embracing arms 6, the cable and wire bearer neck 7, and the overlapping 30 hooks 9, constituting an open or split ring 10; substantially as described.

EUGENE S. BRADFORD.
